UNITED STATES PATENT OFFICE

2,111,875

POWDER DISPENSER

Russell Kenneth Swanson, St. Joseph, Mo.

Application August 12, 1936, Serial No. 95,637

1 Claim. (Cl. 221—106)

This invention appertains to new and useful improvements in dispensers for powder, and more particularly for tooth powder.

The principal object of the present invention is to provide a powder dispenser from which powder can be dispensed in measured quantities.

Another important object of the invention is to provide a powder dispenser from which powder can be dispensed in predetermined quantities and in which the powder will be kept agitated as it is dispensed.

Other important objects and advantages of the invention will become apparent to the reader of the following specification.

15 In the drawings:

Figure 1 represents a rear elevational view of the dispenser.

Figure 2 represents a side elevational view of the dispenser, with parts in section.

20 Figure 3 is a front elevational view of the dispenser with parts in section.

Figure 4 is a horizontal sectional view taken substantially on line 4—4 of Figure 1.

Referring to the drawings, wherein like numerals designate like parts, it can be seen that numeral 5 represents the hopper or container for powder or other pulverized material, which is provided with a hopper 6 at its lower end having an upstanding flange or wall portion 7 adapted to slip over the lower portion of the container 5. The lower portion of this hopper 6 is of cylindrical shape as denoted by numeral 8 and is provided with an elongated discharge mouth 9 extending longitudinally of the cylindrical portion 8.

35 Snugly operative in the cylindrical portion 8 of the hopper is the drum 10 having longitudinally extending channels 11 therein, each of which is of substantially the same length as the discharge mouth 9 so that as the drum 10 is rotated by the knob 12, these channels as they fill from the container 5 will be carried around by the drum and discharge through the mouth 9.

40 Numeral 13 represents the spring member secured as at 14 to the inside of the hopper 6 and this extends over the drum 10 and has the upstanding semi-cylindrical shaped spring agitator 15 secured thereto. A divergent depending spring member 16 is also provided on the spring 13, the

50 same being bent backwardly at its lower end as

at 17 to provide a head portion which can engage in the channels of the drum 10 and this engagement of the head 17 in the channels as the drum is rotated will vibrate the spring 15 so as to always keep the contents of the container loosened and 5 in a pulverized state.

The container 5 is supported upon the wall bracket 18 by the offset upstanding lug 19 at the upper end thereof which extends into a bulged portion 7' of the wall 7 of the hopper 6. A pan 10 20 is supported upon the lower horizontal portion of the bracket 18 for catching the powder which does not settle upon a toothbrush positioned under the mouth 9. Toothbrush supporting hooks 22 depend from this pan 20 and as suggested in 15 Figure 1, openings 23 are provided in the broad portion of the bracket 18 so as to accommodate screws which may be driven into a wall or other supporting structure.

25 While the foregoing specification sets forth the invention in specific terms, it is to be understood that numerous changes in the shape, size, and materials may be resorted to without departing from the spirit and scope of the invention as 20 claimed hereinafter.

Having described the invention, what is claimed as new is:

A powder dispenser comprising a hopper like container having at its lower end a substantially semi-cylindrical portion horizontally disposed and provided with a longitudinally extending discharge slot in the bottom thereof, a closed metal drum fitted in said portion for rotation therein, said drum having depressed peripheral portions 30 extending longitudinally thereof and forming measuring grooves therein adapted to register with said slot, and agitator means in said container comprising a leaf spring secured at one end to a wall of the container and having a free end 35 overlying the drum intermediate the ends thereof, a semi-circular band of flat resilient metal secured intermediate its ends to the free end of said leaf spring in upstanding position to extend longitudinally of the drum, and a hook shaped 40 member depending from the leaf spring to 45 engage the periphery of the drum and seat in said grooves whereby upon rotation of the drum said band is vibrated bodily.

RUSSELL KENNETH SWANSON. 50
